FOLDING STEREO PICTURE VIEWING DEVICE

Arthur H. Crapsey, Jr., Rochester, N. Y., assignor to
Eastman Kodak Company, Rochester, N. Y., a corpora-
tion of New Jersey

Application May 24, 1954, Serial No. 30,629

Term of patent 14 years

(Cl. D61—1)

Fig. 1

Fig. 2

To all whom it may concern:

Be it known that I, Arthur H. Crapsey, Jr., a citizen of the United States, residing in Rochester, in the county of Monroe and State of New York, have invented a new, original, and ornamental Design for Folding Stereo Picture Viewing Device, of which the following is a specification, reference being had to the accompanying drawings, forming a part thereof in which:

Fig. 1 is a perspective view of a folding stereo picture viewing device shown in operating position and embodying my new design; and

Fig. 2 is a rear elevational view thereof.

I claim:

The ornamental design for a folding stereo picture viewing device, as shown.
